UNITED STATES PATENT OFFICE

HENRY JOSEPHS, OF BRONX, NEW YORK, ASSIGNOR TO HENRY D. ROBLES, OF BROOKLYN, NEW YORK, AND LEO WOOLMAN, OF NEWARK, NEW JERSEY

PROTECTOR

Application filed July 11, 1931. Serial No. 550,094.

This invention relates to protectors, and more particularly to protectors for preventing undesired rubbing of an article of attire against the part of the body.

5 *Objects.*—Among the principal objects the invention has in view are: to provide a protector adapted more particularly for use with shoes; to prevent the edge of the vamp from wearing against the user's foot or instep; to 10 provide a removable and replaceable means for protecting the wearers instep from the edge of the vamp; to provide a device which will retain itself in place by pressure of the user's foot there against; to secure simplicity 15 of construction and operation; and to obtain other advantages and results as may be brought out in the following description.

In the drawings:

Figure 1 is a perspective view of a shoe 20 partly broken away showing my invention applied thereto and a person's foot being inserted in the shoe;

Figure 2 is a side view of a shoe partly broken away and showing my invention as 25 it appears therein when not engaged by the person's foot;

Figure 3 is a plan of a portion of a shoe showing my invention applied thereto; and

Figure 4 is an elevation of the protector 30 comprising my invention.

In the description:

In the specific embodiment of the invention illustrated in said drawings, the reference numeral 10 indicates the protector in general which is shown as a single piece of material having a curvature substantially that of the upper front edge of the vamp 11 of a shoe 12. This part of the protector having the curvature mentioned provides the curvature 40 in a direction lengthwise of the protector and the same marginal portion of the protector is likewise curled as at 13 so that the protector will have a hooked shape in vertical cross-section. For convenience, this curved and 45 curled edge will be referred to as the upper edge of the protector.

From the curled upper edge of the protector extends a body portion 14 which is curved to underlie the marginal portion of the vamp, 50 and in cross section has a curvature which

normally positions the greater part of the body portion in special relation from the marginal portion of the vamp. The lower edge 15 of the said body portion is adapted to engage the vamp and preferably the material comprising the protector is quite resili- 55 ent so that pressure of the user's foot in the shoe will tend to press the body portion throughout its entire area against the vamp. It is this pressure of the user's foot and def- 60 ormation of the protector from its normal configuration which serves to clamp the device in place and at the same time serves to prevent rubbing since the body portion will spring with movement of the user's foot and thus remain in contact with it as long as the user's foot remains in the shoe.

It may be further noted that the curled edge 13 is somewhat oval in cross-section and provides a recess to receive the binding such as a French edge 16 along the edge of the vamp. The recess is preferably loose with respect to the edging so that the protector will hang upon the edge of the vamp as illus- 70 trated in Figure 2 when there is no foot in 75 the shoe.

When the foot is inserted in the shoe, the lower part of the body portion of the protector is swung forwardly and upward and comes into contact with the vamp as above de- 80 scribed. The somewhat oval shape of the curled edge aids the user in sliding a foot into the shoe.

The device may be readily retained upon a shoe whether in use or not, and may also be 85 readily removed from a shoe if desired to use it with another one or if any other use is desired for the shoe or protector. It is within the scope of the invention to manufac- 90 ture the protector in any colors desired either to simulate the color of the shoes or to contrast therewith as may be found desirable. I further deem it within the scope of the invention to employ any desired material, such as celluloid, rubber, metal and so forth so 95 long as the device is not bulky and has a sufficient resiliency. Furthermore, other de- 100 tail changes and modifications may be made in the construction and use of my improved protector without departing from the spirit

or scope of the invention, and I do not wish to be understood as limiting myself to the exact construction as shown or described, except as set forth in the following claims

5 when construed in the light of the prior art.

Claims:

1. A device as characterized a body portion having a curved and curled upper edge adapted to be applied to the edge of a vamp 10 of a shoe, said body portion extending from said curled edge and adapted to underlie the marginal portion of the said vamp in use, and said curled edge overlying the body portion substantially an amount corresponding to the 15 diameter of the curl.
2. A device as characterized a resilient body portion having a curved and curled upper edge adapted to be applied to the edge of a vamp of a shoe, said body portion extending 20 from said curled edge and adapted to underlie and resiliently press against the marginal portion of the said vamp in use, and said curled edge overlying the body portion substantially an amount corresponding to the 25 diameter of the curl.
3. A device as characterized for use with a shoe having a binding at the edge of the vamp thereof, a protector having a recess to receive said binding the front portion of said 30 protector forming the recess having a depth substantially equal to the width of the binding and said protector having a body portion for underlying the portion of the vamp adjacent said binding.
- 35 4. A device as characterized for use with a shoe having a binding at the edge of the vamp thereof, a resilient protector having a recess to receive said binding whereby the protector may be hung on the binding, said 40 protector having a body portion adapted to be swung into the shoe toward the vamp by insertion of the user's foot into the shoe, said body portion having a shape differing from the shape of the vamp both crosswise and 45 longitudinally of the vamp so as to be resiliently pressed against the vamp by the user's foot and thereby prevent rubbing by remaining in contact with the user's foot at all times while in the shoe.
